(57) **CLAIM**

The ornamental design for a street lamp, as shown and described.

DESCRIPTION

FIG. 1 is a top perspective view of a street lamp showing my new design.

FIG. 2 is a bottom perspective view of the street lamp shown in FIG. 1;

FIG. 3 is a front view of the street lamp shown in FIG. 1;

FIG. 4 is a right side view (the left side view being a mirror image thereof) of the street lamp as shown in FIG. 1;

FIG. 5 is a rear view of the street lamp shown in FIG. 1;

FIG. 6 is a top plan of the street lamp shown in FIG. 1; and,

FIG. 7 is a bottom plan of the street lamp shown in FIG. 1.

Broken lines illustrate portions of the article and form no part of the claimed design.

1 Claim, 2 Drawing Sheets
